DRILL GRINDING APPLIANCE

Gordon D. Hardin, Louisville, Ky.

Application July 21, 1932, Serial No. 623,720

10 Claims. (Cl. 51—219)

The present invention relates to a drill grinding appliance, and more particularly to a device, associated with a grinding wheel, and operable to move a lip drill with relation to the grinding wheel in such a manner as to produce a drill point having a much longer serviceable life than has heretofore been considered possible.

A primary object of the invention is to provide an extremely inexpensive but highly efficient tool which may be used in small shops or on the job to grind lip drill points, and which will produce a point which is superior in every respect to a hand ground drill point and superior in some respects to drill points ground on much more expensive machines which are now on the market. A further object of the invention is to provide a device of the character described in which all movements of the drill during grinding shall be in a straight line constituting the axis of the drill, but of such character as to produce a drill, in which relief is provided immediately in advance of the chisel edge, whereby that edge is permitted to cut instead of grinding during operation of the drill.

A further object of the invention is to provide a mechanism of the character described including means for automatically advancing the drill upon rotation thereof to produce the above mentioned relief in exactly proper proportions throughout the surface of the lands of the drill. A further object of the invention is to provide, in a device of the character described, means for effecting such advancing movement of the drill, such means being of such character as to be adjustable to accommodate the mechanism to drills of varying sizes, the adjusting mechanism being graduated so that it may be readily set to the proper position for a drill of given size by an inexperienced operator.

A further object of the invention is to provide a device of the character described which, after an initial careful positioning, may be readily removed from its association with the grinding wheel and thereafter readily reassociated with the grinding wheel in the proper relation thereto.

Further objects of the invention will appear as the description proceeds.

To the accomplishment of the above and related objects, my invention may be embodied in the form illustrated in the accompanying drawing, attention being called to the fact, however, that the drawing is illustrative only, and that change may be made in the specific construction illustrated and described, or in the specific steps

stated, so long as the scope of the appended claims is not violated.

Fig. 1 is a plan view of a device constructed in accordance with the present invention showing a drill in association with the grinding wheel; 5

Fig. 2 is a side elevation of such mechanism, parts being broken away for clarity of illustration;

Fig. 3 is a fragmentary end elevation taken from the left of Fig. 1; 10

Fig. 4 is a transverse section of a detail upon an enlarged scale, and

Figs. 5 and 6 are sectional views of still other details of the novel structure.

Referring more particularly to the drawing, 15 it will be seen that I have illustrated a grinding wheel 10 suitably mounted upon a fixed axis 11. Assuming that the grinding wheel 10 is positioned above a table or bench indicated at 61 in Fig. 2, a foot piece 12 having apertured ears 13 is positioned upon the table adjacent the grinding wheel 10. Said foot piece is provided, in the illustrated embodiment, with a tongue 14 which may, or may not, be slightly flared to form a dovetail. The foot piece 12 is so oriented with respect to the wheel 10 that the adjacent longitudinal edge of the tongue 14 is parallel with the outer flat face of the grinding wheel 10; and the foot piece is fixed in this position by lag screws, or the like, extending through the apertures of the ears 13 and threaded into the bench 20 61. The foot piece 12, once having been positioned is intended to be permanently maintained in that position.

A base member 15 is formed with a groove 16 35 adapted to mate with the tongue 14, and said base member is provided with a slot 17 adapted to receive a machine screw 18 which takes through said slot 17 and threads into a suitably provided socket in the tongue 14 to clamp the 40 base member 15 in adjusted position on the foot piece 12. It will be perfectly obvious that, once the foot piece 12 has been positioned properly with respect to the grinding wheel 10, the base member 15 may be readily associated with 45 said foot piece and will thereby be properly oriented with the grinding wheel 10. In small shops particularly, it is highly desirable that the base member and its associated elements shall be readily removable and replaceable in 50 its relation to the grinding wheel 10 so that said grinding wheel may be available for other work and may not be obstructed by the drill grinding appliance. The slot 17 and clamping bolt 18 permit adjustment of the base member 15 with 55

respect to the grinding wheel 18, but the mating tongue 14 and groove 16 limit such adjustment to movement in a line parallel to the flat face of the wheel 18.

5 The base member 15 is formed to provide a longitudinally extending slot 19 in which is mounted a screw 20, the screw being so mounted as to be rotatable with respect to said base, but to be held against any other movement with respect thereto. A hand wheel 21 is secured to the screw 20, preferably beyond the limits of the base member 15, whereby said screw 20 may be manipulated.

10 The slot 19 is bounded by upstanding rails 22 upon which is slideable a carriage indicated generally at 23. As is clearly shown in Fig. 1, the slot 19 and screw 20 are so positioned that their axes intersect the flat surface of the wheel 18 in an acute angle. The desired angle for drill 15 grinding operations is well known, and consequently it needs simply to be stated here that the device of the present application is so constructed as to cause the drill to engage the flat surface of the grinding wheel 18 in the desired 20 angle.

15 Two pins 24 are reciprocably mounted in apertures 25 in the base of the carriage 23, one of said pins being positioned on one side of the screw 20 and the other being positioned on the 20 other side thereof. At their lower ends, said pins are rigidly connected to a threaded member 26 which may be termed a half-nut, said member being positioned beneath, and being adapted to engage, the screw 20. Coiled springs 25 27 are sleeved over said pins 24 and engage between the base of the carriage 23 and the heads of the pins 24, whereby said springs tend to hold the threaded member 26 normally in operative engagement with the screw 20. It will be 30 obvious that the heads of the pins 24 may be engaged by the fingers of an operator to depress the pins 24 against the tendency of the springs 27 to release the operative engagement of the member 26 with the screw 20, whereupon the 35 carriage 23 may be manually moved upon the rails 22.

40 The engagement of the pins 24 in the apertures 25 forms a driving connection between the element 26 and the carriage 23. Furthermore, 45 the carriage 23 is provided with depending lugs which are bored as at 28 to receive loosely the screw 20. The member 26, when in engagement with the screw 20, is snugly received between the bored lugs, whereby it may be said there is a 50 driving connection between the member 26 and the said bored lugs.

55 Adjacent the end of the base 15 nearest the grinding wheel 18 there is provided an upstanding hub 29 formed with a smooth-bored socket 60 receiving a threaded stem 31. Said stem is preferably provided with a longitudinally extending slot into which may project the inner end of a set screw 32 threaded through the hub 29. A knurled nut 33 is threaded on said stem 65 31 and rests upon the upper end of the hub 29. At its upper end, the stem 31 supports a V-shaped rest 34 the function of which will be described hereinafter.

70 It will be obvious that the adjustment of the stem 31 and consequently of the rest 34 may be effected by releasing the set screw 32 and rotating the nut 33 in one direction or the other whereby, since the stem 31 is held against rotation by the engagement of the screw 32 in the 75 above-mentioned slot, said stem is threaded

through said nut either upwardly or downwardly, depending upon the direction of rotation of the nut 33. After the height of the rest 34 has been suitably adjusted the screw 32 may be turned down to hold said stem in adjusted position.

75 The carriage 23 supports a bored hub 35 the axis of the bore of which is parallel with the axis of the bore of the screw 20. In the bore of said hub 35 there is reciprocably and rotatably mounted a spindle 36 on the rear end of which is mounted a hand wheel 37. A coiled spring 38 is sleeved over that portion of the spindle 36 between said hub 35 and said hand wheel 37, and said spring abuts at one end against the hub 35 and at its 15 opposite end against the hand wheel 37, thus biasing the spindle 36 toward the right as viewed in Figs. 1 and 2. On the opposite end of the spindle 36 is mounted a chuck 39 of any desired 20 type, said chuck being adapted to engage and hold a drill 40. The particular embodiment of my invention illustrated in the accompanying drawing is adapted for use in the sharpening of drills of any size up to and including one-half 25 inch diameter, but it will be obvious that, without inventive modification, the mechanism herein disclosed may be adapted for handling drills of larger diameters.

30 A pin 41 is rigidly mounted in a transverse bore extending through the spindle 36 so that the 35 opposite ends 41' and 41'' of said pin project radially oppositely from said spindle. A cam housing 42 is suitably carried by the carriage 23, said housing being formed with a groove 43 which is traversed by a pivot pin 44 upon which is oscillatably mounted a cam block 45. Said block 45 is formed with a cam face 46 projecting beyond the grooved surface of the housing 42, and said cam face 46 is disposed in the path of the 40 ends 41' and 41'' of the pin 41. Thus it will be 45 seen that, as the spindle 36 is rotated, the pin ends 41' and 41'' will successively engage and be moved by the cam face 46.

50 Adjacent its upper end, the housing 42 is formed with a threaded bore 47 in which is 55 mounted a screw 48 provided at its outer end with a knurled knob 49. A coiled spring 50 has its one end mounted in a socket 52 formed in the lower end of the housing 42, the opposite end of said spring 50 engaging the short lower 55 arm 51 of the cam block 45, and thereby urging the upper arm of said cam block into contact with the inner end of the screw 48. It will be 60 obvious that rotation of the screw 48 in a clockwise direction, as seen in Fig. 6, will cause clockwise rotation of the cam block 45, as viewed in Fig. 5, against the tendency of spring 50.

65 As is clearly shown in Fig. 4, the lower and upper ends 53 and 54 of the cam face 46 are bevelled off on lines radial with respect to the center of the spindle 36, whereby the pin ends 41' and 41'' are substantially parallel with said 70 ends 53 and 54 when they engage and leave said cam face 46.

75 The rear face of the knob 49 is preferably provided with graduations, as illustrated in Fig. 6. In the illustrated embodiment, the numbered 80 graduations represent sixteenths of an inch in drill diameters. Thus, when the knob 49 is in the position illustrated in Fig. 6, wherein the graduation "1" is in registry with the scored line 56 on the hub 35, the cam block 45 is properly positioned for grinding a drill one sixteenth of an 85 inch in diameter.

90 It will be obvious that, as the spindle 36 is ro- 75

tated, the pin ends 41' and 41" will ride over the cam face 46, thus reciprocating the spindle 36 to advance and retract the drill 40 with respect to the grinding wheel 10. Clearly, therefore, the drill 40 must be properly indexed with relation to the rotative position of the spindle 36 before grinding is initiated. To provide for such proper indexing, I have evolved the following arrangement. At a point on the spindle 36 which is disposed within the hub 35, I provide a radial socket 57. The hub 35 is formed with a radial bore 58, and the socket 57 is so positioned that, when the pin end 41' is in the position illustrated in Fig. 4, wherein it has just mounted the lower end 53 of the cam face 46, the socket 57 is in registry with the bore 58. I prefer to provide a pin 59 which, in the illustrated embodiment, is an end of a tool 60 which forms a part of the equipment, and to enter said pin 59 through the bore 58 and into the socket 57, thus locking the spindle 36 in the indicated position. Thereafter, a drill 40 to be ground is entered in the chuck 39 and is rotated until one cutting lip of said drill is in an absolutely horizontal position. While a skilled operator can usually position the drill properly by measuring the position of the critical cutting lip with his eye alone, it is desirable for one who is not skilled in the use of the machine to follow the following procedure. The set screw 32 is loosened and the nut 33 is rotated until the upper end of the V rest lies in the plane occupied by the center point of the drill 40. A straight edge is then rested upon the upper ends of the wings of V, and the drill is rotated until one of the cutting lips thereof comes into parallelism with the lower edge of the straight edge. The chuck 39 is then tightened, care being taken to prevent movement of the drill 40 during such tightening.

40 The nut 33 is now operated to elevate the V rest 34 into a position wherein the sides of the socket lightly engage the periphery of the drill 40, whereby said rest forms a support for the drill to prevent bending thereof during the grinding operation, it being understood that the wheel 10 will be rotated in a counter-clockwise direction as viewed in Fig. 3. The carriage 23 is now advanced to the position illustrated in Fig. 1, wherein the point of the drill projects just beyond the forward end of the rest 34, rough positioning of the carriage being effected by releasing the engagement of the member 26 with the screw 20 and final adjustment of said carriage being effected by manipulation of the hand wheel 21.

It is to be noted that the base member 15 must be so adjusted upon the foot member 12 that, when the drill is brought fully into contact with the flat face of the wheel 10, the spindle 36 being locked in position by the pin 58, one cutting lip of the drill will contact the grinding wheel in a line parallel to, and spaced below the horizontal diameter of said wheel, the center point of the drill being positioned very slightly beyond the peripheral edge of said flat face. The machine herein disclosed is so designed that the drill must engage the wheel at a point below the horizontal diameter, the optimum point being dependent upon the diameter of the wheel. 70 However, in a machine having the range of the embodiment illustrated herein, an arrangement such that the cutting lip engages wheels from 6 to 12 inches diameter in a line spaced one inch below the horizontal diameter thereof will give 75 satisfactory results in grinding drills within the

capacity of the machine. While this compromise position is generally satisfactory, extreme nicety may be attained by lining up the machine in such a way as to cause the drill point to engage the face of the wheel at a point spaced forty-five degrees from the horizontal diameter of the wheel; and this recommended adjustment is independent of the diameter of the wheel.

The parts having been set up in the manner above described, the pin 59 is removed from the socket 57 and the bore 58 and the spindle 36 is turned in a counter-clockwise direction as viewed in Fig. 6, whereby the pin end 41' is backed off of the cam face 46. The spring 38 thereupon, of course, retracts the spindle 36 so that a slight clearance is left between the drill end and the grinding wheel 10. Rotation of the wheel 10 is now initiated and, when the wheel has obtained its normal speed, the operator grasps the hand wheel 37 and turns the spindle 36 in a clockwise direction as viewed in Fig. 6. As the spindle is turned, the pin end 41' again rides up on the end 53 of the cam face 46, thus moving the drill into contact with the face of the wheel 10. Further rotative movement of the spindle 36 causes further advancement of said spindle and the drill, whereby the center point of the drill is caused to project farther beyond the peripheral edge of the wheel 10, and whereby the following portion of the drill land is brought into contact with the grinding wheel. The cam face 46 is so designed that it automatically effects a sufficient advancement of the drill 40 to grind the drill land in such a manner as to give an optimum relief to said land and to provide an increasing relief adjacent the chisel point of the drill. The pin end 41' drops off of the end 53 of the cam face 46 just as the rear edge of the drill land leaves its contact with the wheel face, whereby the spring 38 is permitted to retract the drill 40, again providing a clearance between said drill and the wheel, and preventing grinding off of a portion of the chisel edge of the drill. The pin end 41" rides up onto the end 53 of the cam face 46 just in time to bring the second lip of the drill properly into contact with the wheel 10.

I prefer to recommend to unskilled operators that they turn the spindle through two complete revolutions before moving the carriage 23 from its initial position of adjustment in order to be certain that both lips have been given a sufficient length of time in contact with the grinding wheel. Skilled operators, however, can obtain substantially perfect results by giving the spindle only one revolution between advancement of the carriage.

After both lips of the drill have been satisfactorily ground from the initial position of the carriage, the spindle 36 is left in a position wherein the pin end 41' is just ready to mount the end 53 of the cam face 46, and the hand wheel 21 is manipulated to advance the carriage slightly. Thereafter, the spindle 36 is again rotated, and this procedure is continued until a satisfactory point has been provided for the drill.

It will be obvious that the device of the present application is extremely simple and inexpensive to manufacture; that it has few delicate parts which will be subject to damage or breakage, so that it can be handled comparatively roughly with safety; and that it is capable of operation by a decidedly unskilled worker to produce excellent drill points. It is also obvi-

ous that the device of the present application is adaptable to uses for which other machines known to me are entirely unadaptable; such adaptability being largely due to the simplicity, smoothness, lightness, ruggedness and ease of adjustment of the device of the present invention.

I claim as my invention:

1. In combination with a grinding wheel, means for properly positioning a drill to be ground on said wheel, comprising a foot member fixedly positioned with respect to said wheel, a base member, cooperating guide means on said foot member and on said base member for guiding movement of said base member, when associated with said foot member, along a line parallel with a plane face of said wheel, a carriage mounted on said base member, means for moving said carriage, upon said base member, on a line intersecting said wheel face in an acute angle, drill-holding means carried by said carriage, and means for reciprocating said drill-holding means in both directions with respect to said carriage, along said last-mentioned line, upon rotation of said drill-holding means in one direction, said last-named means including a cam.
2. In a drill-grinding appliance, a base, a carriage mounted on said base, a screw mounted on said base for rotation about an axis extending longitudinally of said base, means carried by said carriage and cooperable with said screw to effect movement of said carriage with respect to said base upon rotation of said screw, a drill holder mounted on said carriage for rotation about its own axis and for reciprocation with respect to said base, means holding said drill holder against all other movement with respect to said base, and cooperative cam means carried by said carriage and by said drill holder to effect reciprocation of said drill holder upon continuous rotation thereof, one of said cam means being adjustable to vary the degree of reciprocation of said drill holder upon rotation thereof.
3. In a drill grinding appliance, a base provided with a cylindrical hub, a drill holder mounted in said hub for reciprocation and rotation with respect thereto, and cam means for effecting reciprocation of said holder upon rotation thereof, said hub and holder being provided, respectively, with a bore and a socket, and said bore and socket being of corresponding diameters and being aligned with each other in one relative position only of said hub and holder.
4. In a device of the character described, a base, a drill holder mounted on said base for reciprocation and rotation with respect thereto, resilient means tending to retract said holder, a plurality of radially oppositely projecting fingers carried by said holder, a cam block mounted upon said base and disposed in the path of movement of said fingers, said block being oscillable about an axis disposed substantially in the plane of initial contact of said fingers with said cam block, and means for effecting predetermined variations in the position of said block, said fingers and block cooperating, at times, to advance said holder against the tendency of said spring.
5. In a drill grinding appliance, a member having a substantially horizontal bore, a spindle reciprocably and freely rotatably mounted in said bore, a chuck carried at one end of said spindle for receiving a drill, two fingers fixedly associated

with said spindle and projecting oppositely therefrom, the axes of said fingers being radial with respect to said drill holder, a cam mounted adjacent said spindle and positioned in the path of said fingers, means associated with said spindle and resiliently urging the same in a direction to hold said fingers against the face of said cam, and means for varying the effect on said chuck of the cooperation of said cam and fingers.

6. In a drill grinding appliance, a member having a substantially horizontal bore, a spindle reciprocably and freely rotatably mounted in said bore, a chuck carried at one end of said spindle for receiving a drill, two fingers fixedly associated with said spindle and projecting radially oppositely therefrom, an element pivotally carried on said member and positioned in the path of said fingers, means operable to swing one end of said element toward said chuck, and means associated with said spindle and resiliently urging the same in a direction to hold said fingers in contact with said element.

7. In a drill grinding appliance, a member having a substantially horizontal bore, a spindle reciprocably and freely rotatably mounted in said bore, a chuck carried at one end of said spindle for receiving a drill, two fingers fixedly associated with said spindle and projecting radially oppositely therefrom, an element pivotally carried on said member and positioned in the path of said fingers, means operable to swing one end of said element toward said chuck, said last-named means being graduated to indicate the degree of movement thereby of said element, and means associated with said spindle and resiliently urging the same in a direction to hold said fingers in contact with said element.

8. In a drill grinding appliance for association with a grinding wheel, a member having a substantially horizontal bore, a spindle reciprocably and freely rotatably mounted in said bore, a chuck carried at one end of said spindle for receiving a drill, a spring associated with said spindle and urging the same away from said wheel, means limiting movement of said spindle under the influence of said spring, two fingers fixedly associated with said spindle and projecting radially oppositely therefrom, a cam element pivoted at one end adjacent said spindle and presenting its cam face toward said wheel, the end of said cam face adjacent the pivoted end of said element being positioned to be substantially tangentially engaged by said fingers, upon rotation of said spindle, at times when said spindle is at the limit of its movement under the influence of said spring, and the opposite end of said cam face being closer to said wheel than is said first-named end.

9. In a drill grinding appliance for association with a grinding wheel, a member having a substantially horizontal bore, a spindle reciprocable and freely rotatable in said bore, a chuck carried at one end of said spindle adjacent said wheel for receiving a drill, a spring associated with said spindle and urging the same away from said wheel, means limiting movement of said spindle under the influence of said spring, two fingers fixedly associated with said spindle and projecting radially oppositely therefrom, a cam element pivoted at one end adjacent said spindle and positioned in the path of said fingers, and means for swinging the free end of said element toward said wheel.

10. In a drill grinding appliance for association with a grinding wheel, a member having a sub-

stantially horizontal bore, a spindle reciprocable and freely rotatable in said bore, a chuck carried at one end of said spindle adjacent said wheel for receiving a drill, a spring associated with said 5 spindle and urging the same away from said wheel, means limiting movement of said spindle under the influence of said spring, two fingers fixedly associated with said spindle and project-

ing radially oppositely therefrom, a cam element pivoted at one end adjacent said spindle and positioned in the path of said fingers, and means for swinging the free end of said element toward said wheel, said last-named means being graduated to indicate the degree of movement thereby of said element. 5

GORDON D. HARDIN.
